UNITED STATES PATENT OFFICE.

ALBERT E. GORDON, OF TRENTON, NEW JERSEY, ASSIGNOR TO AJAX-GRIEB RUBBER COMPANY, OF NEW YORK, N. Y., A CORPORATION OF NEW JERSEY.

STOPPER-RETAINER.

950,387.

Specification of Letters Patent. Patented Feb. 22, 1910.

Application filed May 15, 1909. Serial No. 496,100.

To all whom it may concern:

Be it known that I, ALBERT E. GORDON, a citizen of the United States, and resident of Trenton, in the county of Mercer and State 5 of New Jersey, have invented a new and useful Stopper-Retainer, of which the following is a specification.

My invention relates to a stopper retainer and more particularly to a retainer for the 10 stopper of what is commonly known as a hot water bag.

The object is to provide a retainer which will permit the stopper to be readily screwed into and out of the nozzle of the bag and 15 which will retain the stopper within convenient reach when out of use and at the same time be sufficiently rigid to make it easy to manipulate it and be capable of ready removal from the bag when for any purpose 20 its presence is annoying, as for instance, in cleansing the bag and stopper.

A practical embodiment of my invention is represented in the accompanying drawings in which,

25 Figure 1 is a view of the top of a bag showing the stopper and its retainer in the position which they occupy when the stopper is in position to close the bag, Fig. 2 is a central section through the same, Fig. 3 is 30 a similar section showing the stopper and its retainer in the position which they occupy when the bag is open, Fig. 4 is an edge view of the retainer in detail, Fig. 5 is a face view of the same, and Fig. 6 is an end view of the 35 same.

The body of the bag is denoted by 1, the nozzle with its internal screw-thread, by 2, the funnel extending from the nozzle by 3 and the handle for carrying or hanging the 40 bag, by 4.

The stopper with its exterior screw-thread to fit the nozzle is denoted by 5 and is provided with a handle or finger piece 6, for screwing and unscrewing it. The finger 45 piece 6 is here shown as formed of wire in the form of a loop, having a contracted or narrower neck portion in proximity to the stopper and widening out as it extends away from the stopper.

50 The stopper retainer is here shown as formed of a single piece of wire, bent intermediate of its ends to form a circular eye 7 for loosely embracing the neck of the finger piece 6, the diameter of the eye being less

than the width of the wider portion of the 55 finger piece beyond the neck, the two parts or branches of the retainer extending from the eye 7 where they normally rest in contact or nearly in contact, away from the eye, at an angle to the plane of the eye, gradually 60 separating from each other and finally turning abruptly away from each other and curving around toward each other to form an elongated loop 8 for the reception of the bag handle 4. The ends of the wire as they approach each other to form the loop 8, rest normally in proximity to each other but may be sprung apart to pass the neck of the finger piece on the stopper into position within the eye 7 and to pass the bag handle into 70 the loop 8, and the retainer may be detached from both the bag handle and stopper at pleasure by springing the branches of the retainer apart.

In use the retainer with stopper connected 75 may be swung over from the position shown in Fig. 3, to that shown in Fig. 2, the loop 8 sliding freely along the bag handle, and the stopper may then be screwed into position, turning freely within the eye 7, and 80 when it is desired to empty or fill the bag, the stopper may be unscrewed and thrown over into the position shown in Fig. 3, thereby moving the retainer entirely out of the 85 way of the nozzle.

The rigid or stiff nature of the retainer renders it convenient to manipulate in swinging it with stopper attached into and out of operative position and when in position to allow the stopper to be screwed into the 90 nozzle, the meeting ends of the branches of the stopper are housed or protected between the parts which form the loop of the bag handle 4. The retainer is furthermore, quite 95 inexpensive, light and durable.

It is obvious that the retainer might assume forms slightly different from that shown and described without departing from the spirit and scope of my invention; hence I do not wish to limit myself strictly to the 100 structure shown, but

What I claim is:

1. A stopper retainer for a hot water bag consisting of an eye for loosely embracing a finger piece on a stopper, a loop for loosely 105 embracing a bag handle and a substantially rigid or stiff portion connecting the eye and loop.

2. A stopper retainer consisting of a wire bent to form an eye at one end for loosely embracing the finger piece on a stopper and to form a split loop at the opposite end to removably embrace a handle.

3. A stopper retainer comprising an eye at one end, a loop at the opposite end and a rigid connection between the eye and loop disposed at an angle to one of the said parts, the eye and loop, and adapted to hold the

eye and loop permanently in their positions relative to the connection.

In testimony, that I claim the foregoing as my invention, I have signed my name in presence of two witnesses, this fourteenth day of May 1909.

ALBERT E. GORDON.
